CARL L. KNUTSON, OF MAYWOOD, ILLINOIS, ASSIGNOR TO CINCH MANUFACTURING CORPORATION, OF CHICAGO, ILLINOIS, A CORPORATION OF ILLINOIS

BINDING POST

Application filed November 28, 1930. Serial No. 498,574.

My invention aims to provide improvements in binding posts.

In the drawing which illustrates a preferred embodiment of my invention:

5 Figure 1 is an elevation view of a binding post attached to a sheet of material for supporting the same;

10 Fig. 2 is a section taken on the line 2—2 of Figure 1 showing a wire engaged with the binding post;

15 Fig. 3 is a section taken on the line 3—3 of Fig. 2; and

20 Fig. 4 is a section taken on the line 4—4 of Fig. 2 but showing the normal relation 15 of the parts before a wire is held in position by them.

25 Referring to the embodiment of my invention illustrated by the drawing, I have shown a binding post for making an electrical connection. The particular binding post illustrated has a central post part 1 pressed from sheet metal and being hollow, as shown in Fig. 2. The central post part 1 has a base 1^a clenched over the head 2 of an attaching screw 3 and the screw passes through a supporting part 4 and receives a nut 5 whereby the post is fixed relative to the support.

30 My improved device also includes a sleeve part 6 which fits over the post part 1 and is adapted to slide relative thereto. In the sleeve part 6 I have cut a notch 7 at one side which is adapted to cooperate with a notch 8 formed in the side of the post part 1 to receive a wire 9, as shown in Fig. 2. The sleeve part 6 is secured in assembled relation with the post part 1 by means of a flange 10 (Fig. 2) flaring outwardly from the reduced end portion 11 of the part 1 over the upper end of the sleeve 6. A coil spring 12 is interposed between the base 1^a of the post part 1 and an annular shoulder 13 formed by the enlargement 14 of the sleeve 6. Thus, the upper end of the sleeve 6 is pressed by the spring 12 against the flange 10 when no wire is gripped by the binding post. In that case, the notches 7 and 8 are out of alignment, as shown in Figure 1.

45 When the type of wire gripping means 50 illustrated is used, it is desirable to prevent

rotation of the sleeve 6 relative to the post 1 so that the notches 7 and 8 may be brought into alignment by merely pressing upon the sleeve 6. Therefore, I have provided a tongue and groove means to accomplish the 55 desired results. In the drawing the groove 16 is cut in the reduced portion 11 (Figs. 2 and 3) and the tongue 17 provided by bending a portion of the sleeve part 6 into the groove 16. The slot 16 is, of course, long 60 enough to permit the desired sliding movement of the sleeve part 6.

A knob 18, preferably made of insulating material, is suitably attached to the sleeve 6. This knob 18 is hollow and receives the 65 ends of both the sleeve part 6 and the post part 1 (Fig. 2), thereby concealing the ends of said parts and also the tongue and groove means. The bore 19 in the knob 18 is long 70 enough so that the knob may slide with the sleeve 6 relative to the post 1 when moving the sleeve to attach or detach a wire.

75 My improved binding post is strong, durable, easy to manufacture and assemble and is simple and inexpensive in construction.

My device is simple and positive in operation and it is only necessary to press downwardly upon the knob 18 to move the sleeve 6 in an axial line relative to the post part 1 thereby bringing the slot 7 opposite the 80 slot 8 so that a wire may be inserted into the slots or removed therefrom. Upon release of pressure upon the knob 18, the spring 12 presses upwardly upon the sleeve 6 and the wire, if in place, will be gripped 85 tightly between the sleeve 6 and the post 1, as best shown in Fig. 2.

90 While I have illustrated and described a preferred embodiment of my invention I do not wish to be limited thereby, because the scope of my invention is best defined by the following claims.

I claim:

1. A binding post having a central post part adapted to be fixed to a supporting structure, an outer sleeve part slidable upon said central post part, each of said parts having means adapted to register with each other upon movement of the outer sleeve part to receive a wire, a spring interposed 100

- between said parts and a flange on the upper end of said central post part extending over the upper end of said sleeve part to hold said parts and spring in assembled relation.
2. A binding post having a central post part adapted to be fixed to a supporting structure, an outer sleeve part slideable upon said central post part, each of said parts having means adapted to register with each other upon movement of the outer sleeve part to receive a wire, means provided partly by each of said parts and cooperating to prevent relative rotation of the parts, a spring interposed between said parts and a flange on the upper end of said central post part extending over the upper end of said sleeve part to hold said parts and spring in assembled relation.
3. A binding post having a central post part adapted to be fixed to a supporting structure, an outer sleeve part slideable upon said central post part, each of said parts having means adapted to register with each other upon movement of the outer sleeve part to receive a wire, a spring interposed between said parts, a flange on the upper end of said central post part extending over the upper end of said sleeve part to hold said parts and spring in assembled relation and a knob carried by said outer sleeve part at its upper end to conceal the ends of the said parts and provide a pressure-receiving member through which the sleeve part may be moved relative to the central part against the pressure of the spring.
4. A binding post having a sheet metal hollow central post part, an outer sheet metal sleeve part adapted to slide relative to said central post part, notches provided by said parts for receiving and holding a wire, a spring interposed between said parts, a flange on one of said parts cooperating with the other part to limit the movement of the sleeve part relative to the post part in one direction and means providing a tongue and groove connection between said parts to prevent relative rotation thereby insuring alignment of the said notches.
5. A binding post having a post part 1

provided with means whereby it may be attached to a support, a sleeve part 6 slideable relative to said post part 1, a spring 12 interposed between said parts to move the sleeve in one direction, a flange 10 on the post part 1 holding the parts 1 and 6 and spring 12 together and means 7 and 8 provided by the parts 1 and 6 to permit a wire to be gripped by said parts.

6. A binding post having a hollow post part 1, said post part 1 having a base 1^a, an attaching screw 3 secured to said base, a notch 8 in said part 1, a reduced end portion 11 on the said part 1, a groove 16 in said portion 11 and a flange 10 on the upper end of said portion 11, a slideable sleeve part 6 having a notch 7 for cooperation with said notch 8, and held in assembled relation with the post part 1 by the flange 10, a spring interposed between the base 1^a and a shoulder 13 on the part 6, a tongue 17 extending from said part 6 into said groove 16 to prevent turning of the sleeve part relative to said post part 1 and a knob 18 attached to said sleeve part 6 and concealing the ends of the parts 1 and 6 and the groove 16 and tongue 17.

7. A binding post having a sheet metal hollow part adapted to be secured to a supporting structure, a second hollow sheet metal part assembled with the first mentioned part in a slideable relation thereto, means provided by said sheet metal parts for receiving and holding a wire, a spring interposed between said parts and normally moving one of the parts in a predetermined direction relative to the other part, an annular flange extending from one of said sheet metal parts transverse to the axis thereof adjacent to one end, means on the other part 105 for cooperative engagement with said annular flange to limit the relative movement of the said sheet metal parts and an attaching element having a head assembled with the part and being fixed relative to the supporting structure and a shank extending therefrom for passage through the supporting structure.

CARL L. KNUTSON.
